UNITED STATES PATENT OFFICE.

RICHARD C. COLLINS, OF ELMHURST, NEW YORK, ASSIGNOR, BY MESNE ASSIGNMENTS, TO UNITED SHOE MACHINERY CORPORATION, OF PATERSON, NEW JERSEY, A CORPORATION OF NEW JERSEY.

APPARATUS FOR REMOVING DUST.

Application filed March 27, 1917. Serial No. 157,853.

To all whom it may concern:

Be it known that I, RICHARD C. COLLINS, a citizen of the United States, residing at Elmhurst, in the county of Queens and State of New York, have invented certain Improvements in Apparatus for Removing Dust, of which the following description, in connection with the accompanying drawings, is a specification, like reference characters on the drawings indicating like parts in the several figures.

This invention relates to abrading and similar machines and is herein illustrated in connection with a machine for buffing the soles of boots and shoes.

In machines of this type a large amount of dust is generated by the action of the tool upon the work, and dust hoods have been provided the function of which was to carry away this dust. These hoods, however, have not worked satisfactorily for two reasons. In the first place in their construction no account has been taken of the natural path or paths taken by the dust as a result of the rotation of the buffing tool. In the second place no attempt has been made to conserve the draft of the blower system with which the ordinary shoe factory is furnished.

By experiment I have found that when a rotating buffing roll is located in the mouth of an ordinary hood and a shoe is applied to the lower front portion of the roll, the bulk of the dust generated tends to be thrown off in an obliquely upward and backward direction while most of the remainder is carried around the roll after the manner of an atmosphere until it is intercepted by and deposited upon the bottom of the shoe.

One feature of the invention comprises the provision of an improved dust hood for a buffing machine so constructed and so located with respect to the buffing roll that the impulse imparted to the bulk of the dust by the rotating roll will be utilized in creating a draft for carrying off the dust. In the illustrative machine the inlet section of the hood is, so to speak, built around the stream composed of the bulk of the dust; and, in order to maintain this self-created draft or to conserve the force of the draft of a blower system to which the hood may be attached, the remaining section of the

hood is made with its cross-sectional area uniform throughout and substantially equal to the opening of the inlet section. Preferably also, the remaining section of the hood is provided with a general downward inclination whereby the falling particles will aid in maintaining the draft.

These and other features of the invention, including certain details of construction and combinations of parts will be described in connection with an illustrative machine and pointed out in the appended claim.

Referring to the accompanying drawing,

Fig. 1 is a perspective of a portion of a buffing machine in which the present invention is embodied;

Fig. 2 is a cross-section on the line 2—2 of Fig. 1, and

Fig. 3 is a cross-section of a rotating buffing roll with a shoe applied to it showing the approximate paths which the dust tends to follow.

Referring first to Fig. 3, when a buffing roll is rotated in the mouth of an ordinary hood and a shoe presented to said roll in the usual relation as shown, a part of the dust generated is thrown off in an obliquely upward and backward direction approximately as indicated by the arrows 4, and another part is carried around with the roll approximately as indicated by the arrows 6 and deposited on the bottom of the shoe.

Apparently the roll tends both to set up a current of air in the hood and to carry around with it an atmosphere laden with dust. Near the point where the work is presented to the roll there is so much dust that a large part of it is thrown off in about the path indicated by the arrows 4, the direction of this path being apparently the result of centrifugal force and the air currents. It will be understood that Fig. 3 is not claimed to be a strictly accurate representation of the paths of the dust but is presented for the purpose of facilitating an understanding of the invention. One purpose of the present invention is to utilize this phenomenon in carrying away the dust by means of a peculiar construction of dust hood.

Referring now more particularly to Figs. 1 and 2, a shaft 3 adapted to be rotated by a

belt applied to a pulley 5 has mounted upon it buffing rolls 7, two being herein shown. For convenience the hood will be described as having three sections, an elongated inlet 8 extending from the rolls to the locality 9, a chamber 11 which progressively decreases in width but increases in depth from front to back of the machine, and an outlet 13 which is circular in cross-section and is adapted to 10 be connected to a suction pipe. Inasmuch as two rolls are provided in the illustrative machine, the inlet of the hood has two branches separated by a fan-shaped partition 10, but it will be understood that if one long roll 15 were used there would be no branches.

In order to take advantage of the natural conditions illustrated approximately in Fig. 3, the lower wall 12 of the inlet section of the hood extends in a reverse curve from a 20 point below and at the rear of the roll to a point above it in an obliquely upward and backward direction which corresponds approximately to the lower outline of the stream of dust indicated by the arrows 4 in 25 Fig. 3, while the upper wall 15 extends from a point above the roll into close proximity to, or into light contact with, the upper part of the roll. In the illustrative embodiment of the invention a hinged member 17 having 30 a brush 19 fast to it forms the extreme end of the upper wall, the brush being in light contact with the roll. The side walls of the hood have curved edges which lie in close proximity to the ends of the roll and to its 35 periphery. This brush construction, however, is not a part of the present invention except as it forms the extremity of the upper wall of the hood. With the construction thus far described that part of the dust indicated by the arrows 4 in Fig. 3 will shoot 40 up the inlet section of the hood without any substantial opposition because of the ample transverse area of said inlet section, while that part indicated by the arrows 6 will be 45 arrested by the extremity of the upper wall 15, herein shown as the brush 19.

In order to remove all this dust by means of suction it is desirable that the area of a cross-section of the hood at every point of its length should be equal approximately to the said ample area of the inlet or mouth of the hood, since under these conditions a uniform and satisfactory draft will be produced with no variation in the speed of 50 travel of the draft through the hood provided the suction furnished is adequate. Of course, if the air trunks in the shop were very large and the fan which produced the suction were sufficiently powerful, neither 55 the cross-sectional areas of the hood nor the shape and disposition of its walls would greatly matter; but in shoe factories, for 60 which the present invention was devised, the suction available is of only a moderate 65 strength sufficient to remove the dust when

said strength is carefully conserved. With 70 hoods constructed according to my invention however, there is no waste of power in producing the draft nor necessity for providing air trunks of excessive size.

In order to maintain this substantial uniformity in the cross-sectional area of the hood and provide for uniform speed of travel of the draft, the chamber 11 progressively decreases in width and increases in 75 depth from front to back of the machine until it merges into the circular outlet 13, the cross-sectional area of which is substantially the same as that of the rest of the hood at every point of its length. The 80 chamber 11 is preferably given a general downward inclination so that the falling particles will aid in maintaining the draft. The suction pipe, not shown, is of approximately the same size as the outlet 13. It 85 will, of course, be understood that the space enclosed by the fan-shaped partition 10 is dead space and not included in the effective area of a cross-section of the hood.

Hitherto it has been customary to provide 90 hoods with large, wide-open mouths and to pay no particular attention to the interior dimensions of the hoods or to their relation to the dimensions of the suction pipe, with the result that the suction while perhaps 95 adequate if properly applied has been largely wasted and consequently ineffectual. With the present construction the force of the suction, that is the rate of flow of the air, is approximately the same at every point 100 in the hood that it is in the suction pipe. This, in connection with the general shape of the hood and its relation to the rolls ensures a thorough removal of the dust. The inlet of the hood is, so to speak, built around 105 the stream of dust indicated by the arrows 4 in Fig. 3 so that this part of the dust which is thrown off from the roll is afforded a free passage, the force with which it is thrown off being utilized to aid in carrying 110 it away. The extremity of the wall 15, herein shown as the brush 19, blocks the moving zone of dust indicated by the arrows 6 in Fig. 3 whereupon it is caught up by the current flowing through the inlet of 115 the hood and removed.

The invention has been described in connection with a buffing machine in which two arbitrary conditions usually exist, first the mouth of the suction pipe to which the hood 120 is to be connected is located back of the machine at a height from the floor approximately the same as that of the roll, and second the work is presented to the lower forward portion of the roll as shown. It is 125 obvious, however, that the direction of the path of the bulk of that portion of the dust which is thrown off by the roll will depend upon the point on the roll at which the work is presented. For example, if the work 130

were presented at the front of the roll on a horizontal line through the axis thereof, the path of the bulk of the dust thrown off by the roll would be obliquely downward instead of upward as in the illustrative machine. It is also obvious that the chamber 11 may extend in a direction other than the one shown if such other direction is more convenient or desirable.

10 With regard to the path of the bulk of that portion of the dust which is thrown off by the roll, and referring to the broken lines A—A and B—B which indicate planes drawn tangent to the roll at the point of 15 contact and at a point diametrically opposite to said point of contact, it will be noted that a wall of the inlet extends from a point adjacent to the plane A—A to a point in the plane B—B, and that this relation of 20 the inlet to the point of application should hold true at whatever position the work is presented. It should also be noted that the inlet extends in a direction approximately perpendicular to the plane A—A and that 25 the wall of the inlet for a portion of its extent is concentric with the roll 7.

Although the invention has been set forth in connection with a particular machine, it should be understood that the invention is 30 not limited in the scope of its application to the particular machine which has been shown and described.

Having thus described my invention, I claim as new and desire to secure by Letters Patent of the United States:

A machine of the class described having, in combination, a frame, a rotary buffing roll mounted on said frame with its under side unobstructed to allow presentation of the work thereto, a hood through which air is drawn to remove the dust generated by the action of the roll on the work, said hood having an inlet section comprising an inclined upper wall terminating in close proximity to the upper part of the periphery 45 of the roll to intercept the dust carried around by the roll, side walls having curved edges in close proximity to the ends of the roll and a lower wall terminating below and at the rear of the roll and extending 50 obliquely upwardly and backwardly in a reverse curve, and a substantially horizontal chamber decreasing in width and increasing in depth from front to rear and forming a rearward continuation for said upper, side 55 and lower walls, the cross-sectional area of said chamber being constant throughout its extent and substantially equal to the cross-sectional area of the opening between the roll and the adjacent curved wall of the 60 hood to conserve the draft.

In testimony whereof I have signed my name to this specification.

RICHARD C. COLLINS.
